UNITED STATES PATENT OFFICE

124,784

DESIGN FOR AN AUTOMOBILE

Carl M. Sopchick, Johnstown, Pa.

Application June 7, 1940, Serial No. 92,872

Term of patent 7 years

To all whom it may concern:

Be it known that I, Carl M. Sopchick, a citizen of the United States, residing at Johnstown, in the county of Cambria and State of Pennsylvania, have invented a new, original, and ornamental Design for an Automobile, whereof the following is a specification, reference being had to the accompanying drawing, forming part thereof.

In the aforesaid drawing:

Fig. 1 is a side elevational view of an automobile showing my new design;

Fig. 2 is a top plan view thereof; and
Fig. 3 is a front elevational view thereof.

The dominant features of the automobile of my design are shown by full lines in the drawing.

I claim:

The ornamental design for an automobile, as shown and described.

CARL M. SOPCHICK.
